TOOTH RESTORATION AND ANCHORAGE
AND PROCESS OF FORMING SAME

Leonard E. Trinkle, Terre Haute, Ind.

Application September 19, 1935, Serial No. 41,275

6 Claims. (Cl. 32—15)

This invention relates to the art of dental surgery and particularly to artificial restorations and more specifically to the method of anchoring the same to a natural tooth, or teeth, and the appliances and fixtures therefor.

The object of the invention is to simplify the method of applying restorations to the patient in such a manner as to reduce the time required in such work and to cause the minimum amount of work on the natural tooth, or teeth, employed to support the restoration.

Thus, the method hereinafter described provides for the retention of a restoration to one or more natural teeth. It eliminates or minimizes tooth destruction in the preparation for restoration, conserves the translucency of the tooth by eliminating practically all gold or metal from the incisal third of the tooth; thus, allowing light to pass through that thin part of the tooth, which, if backed by opaque material, will cause the tooth to be opaque, thereby giving the tooth a darker color than an adjoining tooth, or teeth, and provides a key or lock for the restoration, such as crowns, inlays, castings, et cetera.

The principal feature of the invention resides in the method of retention of restorations, such as above referred to, through the medium of an inter-locking casting held in place by a screw threaded set screw, reenforced by a cement coating, as distinguished from the usual methods of gripping the tooth under pressure, the employment of inlaid pins, cement, or the like.

Another feature of the invention resides in the employment of means for supporting the set screw in place, such as a threaded sleeve rigid with the casting, whereby the screw may be readily manipulated while held in place, thereby before the cement, in which it is to be imbedded, sets, thus greatly simplifying the mechanics required in setting and locking the restoration in place.

The full nature of the invention will be understood from the accompanying drawing and the following description and claims:

In the drawing, Fig. 1 is a rear elevation illustrating the application of a restoration in bridge form.

Fig. 2 is a plan view thereof.

Fig. 3 is an enlarged perspective view showing the application of a single tooth restoration, the locking screw and supporting sleeve being shown in cross section.

Fig. 4 is an enlarged view of the sleeve in cross section and an elevation of the locking screw.

Fig. 5 is a view similar to Fig. 3 of a modified form of the invention.

In Figs. 1 and 2 of the drawing, there is illustrated a pair of spaced natural teeth 10, a pair of artificial teeth 11 therebetween and supported upon the metal bridge 12. Each end of the bridge is provided with a natural tooth anchorage, such as a casting 13, applied to and interlocked with the natural tooth. In fitting and applying casting 13, the natural tooth is ground to provide one or more grooves or recesses 14 in the back surface thereof, as well as at least one shallow hole or recess 15, see Fig. 3.

This assumes that no restoration is required for the natural tooth. If a restoration of lost tooth structure is required, the proper preliminary reduction of the natural tooth must be made and then the recesses and hole are cut. It is to be understood that basically this invention relates to natural tooth restoration anchorage and consequently bridge anchorage and the like, is ancillary.

The usual impression is made of the rear surface of the natural tooth, as thus prepared, and from it the restoration casting 13 is made. After the restoration casting is formed, the threaded sleeve 16 is soldered or welded thereto and the casting, if it is to constitute a bridge anchorage, is soldered or welded to the bridge or structure 12. The sleeve may be cast in the restoration, if desired. A screw 17 having a threaded lock nut 18 thereon, is threaded into place in the sleeve 16 which is mounted upon the casting. Thus, the screw 17 is held in place by the sleeve, ready for manipulation.

Lock nut 18 is accurately positioned on screw 17 against the exposed end of sleeve 16 after the head 19 has been turned to inwardly seat the end 17a of the screw in the hole 15, such that the restoration is not wedged away from natural seating in or upon the tooth. Cement, as indicated at 21 or its equivalent, on screw 17 between lock nut 18 and head 19, keeps lock nut 18 securely fixed on the screw as a stop or guide to determine the end of the screw 17a is properly seated in hole 15 when the fixture is permanently set or placed. Thereafter, the screw is unthreaded at least until the head 17a does not project beyond the natural tooth engaging surface of the restoration.

When cast therein, the sleeve has external interlocking means thereon such as a rib, ribs, 50 grooves or roughened surfaces, 20 to prevent sleeve rotation in the casting when the screw is threaded inwardly and engages the wall of recess 15. The sleeve provides an elongated bearing for the screw.

The casting, however, may have a boss formed integral therewith which is then drilled and tapped as shown in Fig. 5 which is the equivalent of the sleeve construction. Similar numerals of the one hundred series indicate similar or like parts.

It is to be understood that recess 15 is formed in the natural tooth after the casting is made and its position is located by marking the same 10 on the natural tooth by a marking device applied through the sleeve or like opening in the casting. The hole in the tooth may be made before the impression is taken, if the impression material is a hydro-celloid material. The hole then will be recorded in the model. The tube is placed in 15 relation to said recorded hole in the model and the waxed pattern attached thereto. When soldering the sleeve to the casting, is the type of connection used therebetween, the tube is placed 20 in a small hole in the waxed pattern opposite the hole in the model.

The casting is then removed from the tooth following the marking, then the recess 15 is formed and then the screw adjusted therein, as 25 noted. Then the casting is removed from the tooth and the usual dental cement is applied to the prepared surface of the natural tooth and to the recesses 14 and 15, as well as the interior of the screw sleeve 16 by removing, backing out 30 to a substantial degree, the screw 17. Nut 18 determines the final position of screw 17 for restoration locking and as will be obvious, will prevent wedging separation between the tooth and restoration. The restoration is then mounted in 35 position with the casting, or castings, and fitted over the natural tooth, or teeth, so as to interlock with the cemented undercut recesses 14. In this position, a suitable tool is applied to the head 19 of the screw 17, so that the latter is then screwed 40 into the sleeve until the end 17a of the screw is imbedded and locked in the recess 15 and entirely surrounded by the cement. Nut 18, as stated, determines this positioning by lock nut 18 engaging the end of sleeve 16 or its equivalent. 45 This positioning of the restoration and screw anchorage is accomplished before the cement has become set or hardened and by reason of the fact that the screw is held ready for tightening which immediately after mounting may be quickly accomplished.

The lock nut 18, if desired, may, after being initially positioned, be backed off a slight amount so as to permit the screw 17 with its end 17a to obtain the maximum nesting of the latter in hole 50 15 and then the lock nut 18 when returned to its original determined position, will hold the screw in the sleeve while the cement thoroughly sets. Thereafter, the screw and sleeve are cut off from the casting, as indicated by the line a—a in Fig. 3, so as to leave no objectionable projection after the restoration has been permanently anchored, and then the restoration surface is finished as desired.

While the invention has been illustrated herein 65 as applied to but one type of bridge work and a single tooth restoration, it will be understood that the same method and mediums employed therein are applicable to crowns, inlays and like restorations for the retention on the natural tooth of the 70 metal castings employed therein.

Herein the term "casting" includes the more

technical terms "castings", "swedgings" and "contourings".

This invention claimed is:

1. In the art of dentistry, the method of anchoring a restoration on a permanent tooth, consisting in providing a restoration locking groove in the surface of the permanent tooth to form a restoration anchorage, forming a restoration casting of suitable metal adapted to snugly fit the prepared surface of the tooth, providing a 10 threaded hole in the casting, forming a registering hole in the surface of the permanent tooth in juxtaposition to the recessing, mounting a lock screw in the casting and temporarily locking the casting to the tooth by means of the screw, adjusting a lock nut on the screw to determine the ultimate locking position thereon, backing out the screw to remove the casting, placing cement in the groove and the hole of the permanent tooth, applying the casting to the cemented 20 tooth, screwing the screw into the tooth hole the full limit of travel as determined by the adjusted lock nut and before the cement becomes set, and then cutting off the exposed end of the screw to conform to the exposed surface of the casting. 25

2. A method as defined by claim 1, characterized by the additional step of backing off of the lock nut prior to the cutting off of the exposed end of the screw.

3. In the art of dentistry, the method as defined by claim 1, characterized by the forming of the threaded opening in the casting by the original inclusion of a threaded sleeve projecting beyond the surface of the casting.

4. In the art of dentistry, the method as defined by claim 1, characterized by the forming of the threaded opening in the casting by the original inclusion of a threaded sleeve projecting beyond the surface of the casting, and by the step of backing off of the lock nut prior to the cutting off of the exposed end of the screw. 35

5. In the art of dentistry, a restoration comprising a casting provided with a screw threaded hole therein, said casting being formed to snugly fit a permanent tooth having a prepared surface, 45 a locking groove and a recess formed therein, said casting having a tongue to fit in the tooth groove, a set screw mounted in the threaded hole and adapted for initial positioning in the natural tooth recess with which the hole registers when 50 the casting is positioned upon the tooth, and a lock nut on said set screw for determining the locking position of the set screw for permanent mounting of the casting said lock nut preventing undesirable wedging occurring between the tooth 55 and casting in the final mounting of the set screw.

6. In a dental anchor for application to a prepared surface of a permanent tooth having a locking groove and a recess, a casting having an opening therethrough to register with said recess, a projection on the inner face of said casting to interlock with said groove, an internally threaded sleeve secured to said casting and aligned with said opening, means to rigidly hold said sleeve to said casting, a set screw threaded in said sleeve 60 and adapted to project into said recess, and a lock nut on said screw to engage with said sleeve to determine the degree said screw will project into said recess. 65
